UNITED STATES PATENT OFFICE.

LURA S. BRAINERD, OF MERIDEN, CONNECTICUT.

METHOD OF PRODUCING MOVING PICTURES.

1,307,846.

Specification of Letters Patent. Patented June 24, 1919.

Application filed June 9, 1915. Serial No. 33,102.

To all whom it may concern:

Be it known that I, LURA S. BRAINERD, a citizen of the United States of America, and residing at Meriden, in the county of 5 New Haven and State of Connecticut, have invented a new and useful Improvement in Methods of Producing Moving Pictures, of which the following is a specification.

This invention relates, broadly speaking, 10 to the construction and production of a moving picture display, which involves and embraces the coördination and correlation of pictures, of cartoons, and living characters, whereby a series of pictures can be rapidly 15 and successively displayed upon a screen at the back of a stage, or platform, and at the same time living moving picture actors appear on said stage and the activities of the picture and the moving picture actors are 20 made to coördinate to produce a dramatic result, the camera in the meantime taking a series of moving pictures of said combined display; from the negative film so produced a positive is made which is employed in the 25 manner well known in the art.

In carrying this invention into effect I employ a series of pictures which have been drawn in such a manner as to indicate and provide an apparent action, simulating human action; being pictures, however, they can be made grotesque, and their positions and movements can be exaggerated; correlating and interwoven with these I introduce living moving picture actors and of the 35 joint display I take a single continuous moving picture film.

In order to explain my invention in greater detail, I will proceed to describe it in connection with the accompanying drawings which form a part of this specification.

In these drawings Figure 1 is a perspective view of the apparatus employed by me and this includes, a stage or platform, a background formed by a screen or picture receiving surface and instrumentalities for projecting and taking pictures. Fig. 2 is a detail diagrammatic view in vertical section of the picture projection member. Fig. 3 is a detail diagrammatic view of the camera 45 and its associated parts. Fig. 4 is a detail view of the picture or cartoons, arranged in sequence and mounted upon their carrier. Fig. 5 is a detail view of a clutch in its connected position. Fig. 6 is a similar view 50 showing the disconnected position. Fig. 7

is a perspective view of all the parts. Fig. 8 is a view of the resultant negative film.

In these drawings 1 represents a stage or platform and 2 the screen or other suitable receiving surface at the back thereof. This 60 screen is suitable for projecting pictures upon from which the camera may take photographs for the negative film of the moving picture scenario; it is so arranged as to form a background for the stage or platform and in such a position as that pictures produced therefrom will show the same perspective as those taken from the living models or physical objects on the stage. 3 is a 65 camera or moving picture photographic apparatus.

It is shown in perspective view in Fig. 1 and as a diagrammatic vertical section in Fig. 3. This camera is of the usual type and is provided with a film unwinding member 4 and winding-up member 5. The film is shown at 6, gate at 7, shutter at 8 and condenser at 9. The film feeding lever is shown at 10. This lever is swung in sliding block 11 and is pivoted at 12 to the arm 13 70 the latter turning on center 14; these arrangements are along the lines of the customary commercial apparatus.

In Fig. 2 is shown a complementary arrangement for feeding and supplying the 85 cartoons or pictures. At 15 is an unwinding, and at 16 is a winding-up apparatus; at 17 is a carrier on which are mounted the cartoons or pictures 18, see Fig. 4; this carrier passes from the unwinding apparatus 15 to 90 the winding up apparatus 16, through the gate 19. As the picture passes the gate 19 the light from the lamp 20 passes through lenses 21, from thence through the translucent cartoon 18, thence through condenser 22 95 and is displayed on the screen 2, see Fig. 1.

From this point and place the cartoons so displayed upon the screen 2 are photographed by the camera 3 and the successive pictures are produced on the negative film 6. 100

Synchronism is secured between the operation of the camera and the cartoon projecting apparatus; the latter is shown in its entirety at 23 in Fig. 1.

The main center or shaft 14 is provided 105 with a handle 24. At its other end it has a clutch member 25; this latter is adapted to interlock with member 26 on the shaft 27; the clutch is operated by a handle 28 pivoted at 29; a pin 30 working in a slot 31 is 110

fixed to a ring 32 which latter as it is thrown to the right or left by the lever 28 shifts the member 25 to an operative or inoperative position through the agency of pin 33 which slides in slot 34 of the shaft 14.

- 5 It will be observed that as the shaft 27 rotates the arm 35 will turn in the direction of the arrow; this arm is pivoted at 36 to the lever 37, the latter turning on center 38 in sliding block 39. As the lever 37 moves up and down with the sliding block the upper end of the lever will enter the perforations of the carrier 17 by reason of its back and forth movement and in its 10 descent will draw the carrier down and present another cartoon to be projected.

15 As will be seen the camera apparatus and the projecting apparatus work in unison when connected up. When the cartoon carrier is unwound from the drum 15 and wound up on the drum 16 the instrumentalities hereinbefore described will cause the 20 cartoons to successively pass through the gate 19 and the camera acting in synchronism therewith will take the pictures successively upon the negative film 6.

25 In carrying out this phase of my invention synchronism is effected by means of the teeth 43 and 44 on the clutch members 25 and 26; when the clutch is thrown into closed position and these two teeth come together the film and picture carrier are paralleled and the proper coördination results.

30 35 I will here take up the method of operation of my invention:

Referring to Fig. 7 the living character *a* is seated at a sewing machine or work table left center of stage; a second living character *b* enters, right center carrying a figure or movable *c*; the movable *c* is about to be deposited center stage and in front of *a* when the latter signals *b* to place it in corner right upper center; in doing so *b* places arm 40 partly around waist of movable in carrying out directions of *a*, when the latter dozes off; at which point *b* exits and the figures shown at *d* are projected upon the screen 2 by the lantern 23; these latter figures proceed from 45 a series of cartoons or pictures moving past the projector light through the agency of the carrier 17 the clutch now being placed in operative position as shown on Fig. 5; the light from the projector proceeds along 50 lines 41 and the reflected rays to the camera 3 are received along lines 42; in this way the living moving picture actors and the enacted and correlating scene on the screen 2 are photographed upon the negative film 6 55 at the same time and as a single picture. At the proper moment the living moving picture actor *e* enters on the stage 1; when

60 this character speaks the actor *a* awakens and as she does so the picture characters *d* fade away; the mounted and traveling pictures are shown in Fig. 4; in Fig. 8 I show the resultant negative film; in the first series of pictures is shown the image *a*, *b*, *c*; as *b* goes off leaving *a* and *c* the characters *d* enter on the screen; as the character *e* 65 comes on the characters *d* disappear.

65 70 But it must be understood also that I do and may employ the pictures on the screen, namely the characters *d* to serve as a by-play or explanatory play, or as a coöperating active part of the same scene.

Having thus described my invention the following is what I claim as new and useful therein and desire to secure by Letters Patent:—

80 1. The process of producing a film for moving pictures that consists in arranging a stage in front of a screen, placing a projecting apparatus and camera, introducing objects onto said stage in front of the screen 85 while the camera is in operation, and, without stopping the operation of the camera, changing the condition of the projecting apparatus.

85 90 2. The process of producing a film for moving pictures that consists in arranging a stage in front of a screen, placing a projecting apparatus and camera, with an operative connection between the two, simultaneously projecting pictures on to said screen 95 and introducing objects on said stage, simultaneously therewith photographing said pictures and objects in sets, and, without changing the operation of the camera, operating the connection between the camera and projecting apparatus to control the movement of the latter.

95 100 105 3. The process of producing a film for moving pictures that consists in arranging a stage in front of a screen, placing a projecting apparatus and a camera to reflect rays across the stage to the same points on the screen, projecting a series of moving pictures from the projecting apparatus directly onto the screen, placing living actors 110 upon the stage in front of the screen, taking a series of pictures embodying pictures from the screen and of the living actors, and, without interrupting the operation of the camera, changing the condition of the projecting apparatus.

110 115 In testimony whereof, I have signed my name to this specification in the presence of two subscribing witnesses, this 20th day of April, 1915.

LURA S. BRAINERD.
